RAIL SUPPORT

Application filed June 15, 1929. Serial No. 371,206.

This invention relates to tie plates, and more particularly to an improved compensating type of plate including parts adapted for relative adjustment thereby permitting the supported rail to be raised or laterally shifted as desired.

A primary object of the invention is to provide a tie plate construction which permits of either or both the lateral and vertical adjustment of the rail in a simple and expeditious manner, thereby avoiding the use of shims and washers and permitting of adjustments to a relatively minute degree within a given range. In that connection the invention contemplates means for changing the position of the rail vertically without completely removing the rail from its fastenings, thereby saving much time and labor incident to the change to be effected.

A further object of the invention is to provide a construction whose parts, when once set in their new or adjusted position, may be held rigidly together by the superposed weight or load thereon, thereby avoiding any tendency of the parts to shift or creep out of adjustment.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which

Fig. 1 is an elevational view of one form of the invention.

Fig. 2 is an elevation of another form of the invention.

Fig. 2^a is a horizontal section through the supporting unit B—C.

Fig. 3 is a top plan view of the construction shown in Fig. 2.

Fig. 4 is a side elevation of a modified construction.

Fig. 5 is a top plan view of the bottom plate shown in Fig. 4.

Fig. 5^a is a detail cross sectional view on the line 5—5 of Fig. 5.

Fig. 6 is an elevation of a further embodiment of the invention along the general lines of the invention shown in Fig. 1.

Similar reference characters designate corresponding parts throughout the several figures of the drawings.

In carrying the present invention into effect it is proposed to provide a tie bearing plate proper designated generally as A, the same having mounted thereon a vertically adjustable rail supporting unit consisting of the parts B and C, which is adapted for relative transverse or lateral adjustable engagement with the tie bearing plate A. The upper part B of the rail chair is provided with a channel for receiving the rail base and this seat may be horizontal as shown or inclined in accordance with standard practice to provide the desired cant for the rail. In this connection the lower member C of the rail chair which constitutes a part of the means for effecting vertical adjustment may have a direct bearing engagement with the upper surface of the tie bearing plate, or it may have an indirect bearing through an adjusting plate C' as shown in Figs. 2 to 5 inclusive for overlying and engaging with the tie bearing plate A.

It will therefore be apparent that in all embodiments of the invention the essential features of a tie bearing plate A and a superposed rail supporting unit B—C are utilized, the latter being so constructed as to permit of the vertical adjustment of the rail, while the entire unit B—C or B—C—C' may be moved or shifted laterally or transversely of the longitudinal axis of the rail.

Referring now more specifically to the details of construction for carrying out the foregoing features it may be observed that the upper surface of the tie bearing plate A is provided with a series of serrations, or alternating parallel ribs and grooves, designated generally as 2 and arranged transversely of the plate. These serrations or ribs are adapted to cooperate with similar serrations, ribs or their equivalent 2 on the bottom or height adjusting member C of the rail supporting chair so that by loosening the rail fastenings F the rail support may be moved

toward one edge or the other of the plate and the desired lateral positioning of the rail may be obtained. This form of adjustment is common to all embodiments of the invention.

5 The rail supporting unit B-C in which the upper member B has a seat for the rail R, and the lower member is movable to effect vertical adjustment of the rail, may manifest itself in various structural forms to secure relative elevation vertically of the member B with reference to the member C.

According to Fig. 1 of the drawings, the members B and C consist of rectangular plates of wedge shaped cross-section and having matching diagonal faces each provided with a plurality of shoulders or facets 3 which are preferably flat as shown or may be cupped or rounded, and whereby the side-wise movement of one member with reference to the other will produce a progressively increasing elevation of the upper member B as the same is moved toward the opposite edge of the lower member from that which it occupies initially. Clearly any desired degree of elevation may be obtained if the proper number of proper dimension facets or shoulders are used and the angles of the interengaging faces are such that the superposed weight of the rail will firmly hold the members B and C together so that when all of the members A, B and C are placed under load they will not become disengaged even though the tie plate and rail supporting unit pull away from the heads of the fastenings F and F' as is well known when the tie is compressed under passing wheel loads. Both the members B and C are provided with suitable slots 4 for receiving the fastenings F which also pass through openings in the tie bearing plate A and take anchorage in the wooden tie T. As shown in Fig. 4 the said fastenings F may be formed at their lower ends so as to engage with the tie plate. For guiding the relative transverse movement of the member C on the tie bearing member A, and to also prevent creeping of said member on the tie bearing plate the latter is preferably transversely grooved as indicated at 5 to receive the keying rib 6 on the bottom of the member C.

Figures 2, 2^a and 3 of the invention illustrate the carrying forward of the invention by modifying the rail supporting unit B-C to the extent that they are circular, and the bearing engagement between the two members, instead of being shouldered or stepped in a gradual transverse plane diagonally from one edge to the other of the unit, is obtained by the use of complementary half spiral flights D and D' and E and E', the limits of the half spiral flights being indicated by the dotted line x-x in Fig. 2^a. The faces of these half spiral flights are provided with a plurality of facets or steps 3^a and 3^b which may be inclined, rounded, cupped or sloped in such a

way that the members become self locking when rotatably shifted, and at the same time elevate the upper member B to any desired degree according to the pitch of the flights and the notches engaged.

In the form of the invention shown in Figs. 2 and 4 it will therefore be apparent that the movement of the members B and C relative to each other is rotary instead of rectilinear as in Fig. 1, and therefore to accommodate such movement the slots 4^a in the member C are arcuate shaped. Also both members are provided with wrench or tool engaging lugs B' and C'' to assist and facilitate their adjustment.

Figs. 4 and 5 of the drawings illustrate a construction wherein the members B and C constituting the rail chair are provided with four spiral shouldered flights 6, 7, 8 and 9 as indicated by the dotted lines, x'-x' in Fig. 5 instead of two flights of shouldered steps or risers. Also, the lower part of the rail chair C and the adjustment plate C' which rests on the tie bearing plate A may be provided with a curved complementary rib and groove or equivalent construction 10 which functions as a centering ring for the members C and C'.

Fig. 6 of the drawings represents a further carrying forward of the invention according to Fig. 1 wherein the rail chair B-C instead of being provided with one inclined set of complementary risers or facets is provided with two sets of inclines 11-11 and 12-12 which permit of horizontal adjustment of either the members B or C toward one edge or the other of the tie plate A.

From the foregoing it will be apparent that the present invention which consists essentially of the fixed tie bearing member and the relatively shiftable and adjustable chair provides a wide range of adjustment to compensate for rail wear and tie depression. In country where the ground freezes to six inches or a foot or more it is very common practice for the tracks to heave at highway crossings or other points where drainage is not free. Therefore, this heaving produces a hump which, in a high speed track, is quite troublesome as it may cause rail breakage or damage to trains. To overcome this it is necessary to build easements over the hump as it is very difficult, and nearly impossible when the ground is frozen, to dig the ties down to reduce the hump on account of the heaving. It is ordinarily the practice to place shims under the rails on each side of the hump, grading off to a distant point to form an easement as heretofore indicated. In that connection the construction in the present case and the adjustment therein possible will provide an easy method of setting up such an easement.

Also, as is well known, at present, much time is spent by section gangs in adjusting

the line and surface of the rails. To adjust surface and take vertical depressions out of the rail, the practice is to tamp up underneath the ties. To make horizontal adjustment a number of men shift the track using lining bars to heave it over one way or the other. With the arrangement of the present invention, two men can make the adjustments to accomplish the same purpose within the limits of such adjustments, thereby displacing a greater number of men.

When the features or principles involved are applied to units of circular or spiral configuration, the bearing faces of the notches are disposed from a central point forming angles symmetrically arranged in a circuit around such point. The degree of these angles may be varied to suit the application. When the degree of the angle is zero, the bearing surfaces of the teeth may be made rectangular in shape instead of triangular, that is, the faces of the notches become parallel. When this configuration and arrangement is used, the device becomes self-locking in one direction but not in a direction at right angles to this direction without further provision for locking such as the spikes or fastenings.

Another feature of the invention resides in the adaptation of the invention as a universal tie plate. That is to say, the tie bearing plate A may be attached to the tie at the treating plant or wherever the tie is "surfaced" as is now common practice, doing so by machinery and thereby cutting down the expense of doing it in the field under various adverse conditions.

When the tie arrives in the field it is only necessary to apply the particular fittings to the size of the rail used, fastening them down and in the case of adjustment shown in the drawings, it may be placed to gauge without any changing of spikes or fastenings, or in any way injuring the tie. If at any time it is necessary to change the rail to a different size it is only necessary to substitute the proper rail fitting B to suit the different size rail base and apply the fastenings. This automatically brings the rail in track to standard gauge without any further ceremony.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

We claim:—

1. An adjustable rail support including a tie bearing plate, a rail supporting unit comprising vertically adjustable rail supporting members, and means for adjusting said rail supporting unit laterally of the tie bearing plate.

2. An adjustable rail support including a tie bearing plate, and a rail supporting unit including a member having a rail seat, and a height adjusting member adapted to be interposed between the member having the seat and the tie bearing plate. 70

3. An adjustable rail chair including a tie bearing plate, fastenings for securing said bearing plate to the tie, a rail supporting unit including an upper member having a rail seat and a lower height adjusting member arranged between said upper member and the tie bearing plate, and fastenings for engaging with the rail and passing through the members of said unit and the tie bearing plate to take anchorage in the tie. 75

4. An adjustable rail chair including a tie bearing plate, and a rail supporting unit comprising vertically adjustable rail supporting members each having engaging inclined faces provided with stepped shoulders whereby relative movement between the members will produce elevation of the rail. 85

5. An adjustable rail chair including a tie bearing plate, and a rail supporting unit comprising complementary vertically adjustable rail supporting members each having engaging inclined faces provided with a plurality of mating facets whereby relative movement between the members will produce elevation of the rail. 90

6. An adjustable rail chair including a tie bearing plate, and a rail supporting unit mounted thereon, said unit comprising a pair of complementary members each provided with a plurality of facets arranged in successively lower planes with the facets of one member matching the facets of another member and adapted to rest thereon. 100

7. An adjustable rail chair including a tie bearing plate, and a rail supporting unit mounted on said plate, said unit comprising a pair of complementary members, one face of each of which is provided with a plurality of circularly arranged matching facets extending successively into different planes. 105

8. An adjustable rail chair including a tie bearing plate, and a rail supporting unit mounted on said plate, said unit comprising a pair of complementary members, a face of each member being provided with a plurality of facets extending into different planes and circularly arranged with the top surface of each step sloping downwardly toward the riser portion of the adjacent higher step or facet. 115

9. An adjustable rail chair including a tie bearing plate, and a rail supporting unit mounted on said plate, said unit comprising a pair of complementary circular members whose opposing faces are provided with a plurality of steps defining an arc about the axes of the members, the steps being arranged in arcuate groups each consisting of successively lower steps with the lowest step of one 125

group arranged adjacent to the highest step of the adjacent group.

10. An adjustable rail chair including a tie bearing plate, and a rail supporting unit mounted on said plate, said unit including a pair of circular complementary members each provided with arcuate groups of facets arranged at different elevations, and the lower one of the members of said units having arcuate fastening receiving openings.
11. An adjustable rail chair including a tie bearing plate, and a rail supporting unit mounted on said plate, said unit comprising a pair of complementary superposed members, the adjacent faces of said members being provided with inclined adjusting surfaces each including a plurality of matching facets.
12. An adjustable rail chair including a tie bearing plate, and a rail supporting unit mounted on said plate, said unit comprising a pair of circular complementary members, the adjacent faces of said members being provided with inclined adjusting surfaces each including a plurality of matching facets, the outer periphery of each member being provided with wrench engaging lugs.
13. An adjustable rail support including a tie bearing plate having serrations in its upper surface, and a rail supporting unit having serrations on its bottom face for engaging with the serrations on the tie bearing plate for effecting lateral adjustment of the rail support to adjust the rail to gauge width.

36 In testimony whereof we hereunto affix our signatures.
